FIG. 3.

FIG. 4.

FIG. 2.

UNITED STATES PATENT OFFICE.

WALTER O. AMSLER, OF PITTSBURGH, PENNSYLVANIA.

GAS-PRODUCER.

1,077,578.

Specification of Letters Patent.

Patented Nov. 4, 1913.

Application filed March 14, 1910. Serial No. 549,168.

To all whom it may concern:

Be it known that I, WALTER O. AMSLER, a resident of Pittsburgh, in the county of Allegheny and State of Pennsylvania, have 5 invented certain new and useful Improvements in Gas-Producers, of which the following is a specification.

An object of my invention is to provide a new and improved gas-producer of the 10 rotative or revoluble type of producer.

Further objects of the present invention are to provide means for automatically and 15 positively feeding the producer with fuel, and also to provide a mechanically operated poker for the producer.

In the accompanying drawings, which illustrate an application of my invention, Figure 1 is a central vertical sectional view of a gas-producer embodying my invention; 20 Fig. 2 a top plan; Fig. 3, an elevational view of the upper portion particularly showing the fuel reservoir and the gearing for the mechanically operated poker and fuel feed device; and Fig. 4 a broken vertical sectional view of the poker and feed device.

Referring to the drawings, 2 designates the rotatable producer proper or body provided at its lower end with an annular supporting ring-member 3 having a depending 30 flange 4 adapted to dip into a water seal of an annular ash receiving trough 5. Trough 5 is supported upon a series of roller bearings 6 which latter are mounted on pinions 7 having their bearings in housings 8, said 35 housings 8 in turn being mounted on a base 9.

10 designates a bearing-ring interposed between the rollers 6 and flanges 11 formed on the under surface of the trough 5.

Trough 5 is adapted to be rotated and 40 supports and carries with it the producer body. For the purpose of supporting said producer body I provide the trough with a series of supporting ledges 12 on which portions of the ring-member 3 rest.

45 Trough 5 is provided with a centrally located wall 13 which projects upwardly into the lower end of the producer. This wall 13 is provided with an upper inwardly extending flange 14 and a lower flange 15 and 50 is closed about midway of its height by a plate member 16. The upper flange 14 is designed to support a hood 17 and the lower flange 15 co-operates with the plate-member 16 in forming a water seal for the upper 55 end of an air pipe 18.

The upper end of the producer proper is

provided with a water containing ring-member 19 and located over and closing the top of the producer body I provide a cap-plate 20. Cap-plate 20 is preferably of the form 60 shown and is designed to contain a body of water employed for sealing and cooling purposes. As illustrated, plate 20 is formed with a flange 21 extending above and below the plate, an opening 22 in communication with a gas outlet pipe 23, an opening 24 bounded by a flanged wall 25, the flange 26 thereof being utilized for supporting a double walled bearing member 27 having a flange 28 adapted to rest upon the flange 26. 65

28 designates a rotatable casing arranged in and extending above and below member 27. Casing 28 at its upper end is provided with an annular rack-plate 29 and has its lower end contracted and formed with an 70 engaging flange 30. Flange 30 is adapted to have secured thereto a combined poker and fuel feed device which projects down into the producer and below the surface of the fuel therein. This combined poker and feed 75 device comprises a hollow metallic structure consisting of the poker proper or body 31 and a tube or passage 32 preferably formed integral with the body and designed to pass the fuel out through an opening 33 of the body. The body is formed with an engaging flange 34 similar to the flange 30 of the casing 28 and 35 designates a tip or plug secured to the lower end of the poker. Water may be supplied to the 80 interior of the poker by means of a pipe 36.

Supported over the fixed top-plate by means of posts 37 is a fuel reservoir 38 having at the top thereof a fuel hopper 39, the latter being provided with a counterbalanced bell-valve 40. The reservoir at its discharge end is provided with a depending flange 41 adapted to extend into the rotatable casing 28 and dip into the water in said casing, and it is further provided with 95 a flange 42 entered into the upper end of the tube of passage 32. Within the fuel magazine or reservoir 38 I provide means for positively feeding fuel therefrom to the tube 32. These means may comprise any 100 suitable positive feed device such, for example, as a screw-feed, or they may comprise a plunger device 43 vertically movable in bearings 44 carried by members 45.

The rotatable producer proper and the other 110 movable members as illustrated, are driven by main drive shaft 46, designed to be con-

nected with a motor, not shown, a shaft 47 and gearing connected with said shaft. Thus, for driving the casing 28 and the attached poker and feed device I provide the shaft 46 with a gear 48 adapted to mesh with the teeth of the rack plate 29. The producer body is rotated by means of shaft 47, a gear 49 carried on the upper end of shaft 47 and arranged to mesh with a gear 50 of shaft 46, and a gear 51 carried at the lower end of shaft 47 and designed to cooperate with a toothed member 52 secured to the trough 5.

The means for actuating the plunger 43 comprise a cam 53 mounted on shaft 46, an adjustable two part connecting rod 54 having its upper end secured to a curved bar 55 formed with openings 56. Bar 55 is connected with an end of a shaft 57 located in a sleeve or bearing 58 projecting through the wall of the fuel magazine. Secured to the opposite end of shaft 57 is a connecting rod 59. Connecting rod 59 has an end projected into the hollow plunger and connects with a rod 60, which latter extends down through the plunger and secures a plug 61.

It is evident, without departing from the scope of my invention, that in place of revolving the producer proper as shown and described, the top plate thereof could be made to revolve and the producer body remain stationary.

What I claim is:

1. A gas-producer having a rotatable body, a fixed cover-member, a fuel-reservoir supported above the cover-member, and a combined poker and fuel feeding device in communication with the reservoir and projecting downwardly therefrom into the rotatable body.

2. A gas producer having a rotatable body, a cover-member, a fuel-reservoir, means operable to effect a positive forced feed of fuel from the reservoir, and a combined rotatable fuel feed and poker device extending downwardly into the bed of fuel in the producer.

3. A gas producer having a revoluble body, a fixed fuel reservoir and a revoluble feed device arranged eccentrically of the producer body and in communication with the reservoir and projecting downwardly therefrom into the producer body.

4. A gas producer having a body, a cover-

member, one of said parts being rotatable, a fuel reservoir, and a hollow member constituting a combined poker and fuel feeding device arranged eccentrically of the producer body and in communication with the reservoir.

60

5. A gas-producer having a body, a cover-member, and a combined rotatable poker and feed device projecting into the bed of fuel and having a discharging opening above its lower end.

65

6. A gas-producer having a body, a cover-member, a combined rotatable poker and feed device comprising an inner tube and a casing, said device adapted to extend into the producer below the surface of the contained fuel and having a discharge opening above its lower end, and means for rotating the poker and feed device.

70

7. A gas-producer having a rotatable body, a fixed cover therefor, a fuel reservoir supported above the cover, means for controlling the passage of fuel from the reservoir, a combined poker and fuel feeding device arranged eccentrically of the producer body and in communication with the reservoir and projecting downwardly into the bed of fuel, and operable means for the rotatable members.

75

8. A gas-producer having a rotatable body, a fixed cover-member, a fuel-reservoir, means for controlling the passage of fuel from the reservoir, a rotatable casing and a combined poker and feed device secured to the casing and movable therewith.

80

9. In a gas producer, a combined rotatable charging and poking device comprising a fuel feed tube and an outer casing having a discharging opening communicating with the tube, and operable means for rotating the device.

90

10. The combination with a gas producer having a revoluble body, of a cover-member having a gas exit port, a combined rotatable charging and poking device extending through the cap-plate, and operable means for said device.

95

In testimony wherof I affix my signature in presence of two witnesses,

WALTER O. AMSLER.
